UNITED STATES PATENT OFFICE.

JOHN A. BOEHRINGER, OF SPRINGFIELD, NEW YORK, ASSIGNOR TO HERMAN A. SAFION,
OF NEW YORK, N. Y.

DESIGN FOR A CHANDELIER.

Application filed February 19, 1925. Serial No. 12,422. Term of patent 3½ years.

To all whom it may concern:

Be it known that I, JOHN A. BOEHRINGER, a citizen of the United States, residing at Springfield, in the county of Queens and State of New York, have invented a new, original, and ornamental Design for a Chandelier, of which the following is a specification, reference being had to the ac-

companying drawing, forming part thereof.

The figure is an elevation of a chandelier, showing my new design.

I claim:

The ornamental design for a chandelier, as shown.

JOHN A. BOEHRINGER.
